U. S. PATENT OFFICE.

No. 108.

1861.

Whole No. 1,473.

Cook Stove.

GILBERT KNAPP, OF HONESDALE, PA.

Letters Patent for a Design, No. 108, dated September 3, 1861.

SPECIFICATION.

TO ALL WHOM IT MAY CONCERN:

Be it known, that I, GILBERT KNAPP, of Honesdale, in the county of Wayne and State of Pennsylvania, have invented or produced a new and original design for a Cook Stove, which I term the "Zeta;" and I do hereby declare that the following is a full, clear, and exact description of the same, reference being had to the annexed drawings making a part of this specification, in which—

Figure 1 is a front view of a stove, showing my design.

Figure 2 is a side view of ditto.

Similar letters of reference indicate corresponding parts in the two figures.

This design for stoves relates to that class which is provided with elevated ovens.

A, figure 1, represents the front plate of the fire chamber, which plate is provided with four arched or semicircular beads *a* connected together, the outer beads terminating in pendants *b*, and the letters Z E T A being in the concave or curves of the arched beads.

The side plates *B* of the stove are each provided with two panels, a square one *C* and trilateral one *D*. The panel *C* has beaded edges *c*, and a circular projection at its centre, from which four radial ornaments *d* project. The boundary of the trilateral panel *D* is a simple bead *e*, and within it, at its centre, there is a small circular projection *f*. The upper edges of the side plates *B* have each a border *E*, formed of a serpentine bead *g*, with a small ornament *h* between every alternate arch of the bead. The edge of the top plate *F* of the stove has a

Knapp's Design for a Cook Stove.

modelling, formed of a scalloped ledge *i* and beads *j*. The edge of the hearth plate is also provided with a scalloped ornament *k*.

The front and back plates *G* of the elevated oven are provided each with a centre ornament, formed of an oval head *l*, encompassed by a scalloped rim *m*, while the body is filled up with radial taper concaves *n*, and corner pieces *o*, and a beaded border *p*.

The side doors *H*—see figure 2—of the oven have each an oval ornament *q*, encompassed by a scalloped rim *r*, from which radial taper concaves *s* project. The edges of the doors are provided with a beaded border *t*.

Having thus described my invention, what I claim as new, and desire to secure by Letters Patent, is—

The general configuration of the parts herein shown and described, to form a new and original design for a cook stove.

GILBERT KNAPP.
